United States Patent Office.

H. LOMBARD, OF SAN FRANCISCO, CALIFORNIA.

Letters Patent No. 96,601, dated November 9, 1869.

IMPROVEMENT IN ROTARY STEAM-VALVES.

The Schedule referred to in these Letters Patent and making part of the same.

To all whom it may concern:

Be it known that I, H. LOMBARD, of San Francisco, in the county of San Francisco, and State of California, have invented a new and improved Steam Cut-Off; and I do hereby declare that the following is a full, clear, and exact description thereof, which will enable others skilled in the art to make and use the same, reference being had to the accompanying drawing, forming part of this specification.

The object of this invention is to provide new and useful improvements in steam-valves, whereby the supply of steam may be varied by the action of the governor, as the motion of the engine varies. It is also designed to provide a regulating-valve, capable of supplying and regulating the steam for one or more engines.

The invention consists of a hollow conical or tapered valve, receiving the steam at one end, and delivering it at one side, to ports in a circular tapered seat, leading to the cylinder, and exhausting, through the other side, from the same ports, and at the end opposite the receiving-end, which valve is provided with a central auxiliary valve, connected to the governor, and operating to vary the opening of the live-steam passage; also, to separate the space of the said valve longitudinally, to form the live-steam and exhaust passages, as hereinafter more fully specified.

Figure 1 represents a sectional elevation of my improved valve-device, and

Figure 2 represents a horizontal section of the same.

Similar letters of reference indicate corresponding parts.

A represents a hollow tapered valve, working in a tapered seat, B, which may have six, more or less, plane sides, and a port in each, each set of opposite ports connecting with one cylinder.

The said valve A is to be connected, at C, with the live-steam pipe, and at D with the exhaust. It is provided with a live-steam port, E, on one side, and

an exhaust, F, on the other, the latter considerably larger than the former.

G represents an auxiliary valve, working within the bore of the valve A, and divided into two longitudinal passages, H I, by the wall K, the one open at the receiving-end, and the other at the delivering-end.

From the passage H, a live-steam port, L, opens to the port E of the valve A, and from the passage I an exhaust-port opens to the wide exhaust-port F of the said valve A.

At one side of the port L, and on the exterior wall of the valve G, a segmental block, M, fitting snugly between the surface of the said valve G and the seat B, is bolted to the said valve G.

The valve A makes one complete revolution to each double stroke of the engine, alternately opening all the ports in the seat B to the live-steam and exhaust ports.

The valve G is connected to the governor, by which it is so moved, as the speed varies, that the block M will increase or diminish the breadth of the passage E, and thereby the amount of steam admitted to the ports of the seat B, which will be more or less, according to the time required for the port E to pass the said ports of the seat B, and this time will be varied by the breadth of the said port E, as well as by the speed of the engine.

Having thus described my invention, I claim as new, and desire to secure by Letters Patent—

The combination of the seat B, valve A, and auxiliary valve G, when provided with ports and passages, and arranged for operation, substantially as specified.

The above specification of my invention signed by me, this 17th day of June, 1869.

H. LOMBARD.
